UNITED STATES PATENT OFFICE.

ARNO LIESENBERG, OF NEW YORK, N. Y.

CIGAR-HOLDER.

SPECIFICATION forming part of Letters Patent No. 560,510, dated May 19, 1896.

Application filed December 11, 1895. Serial No. 571,730. (No model.)

To all whom it may concern:

Be it known that I, ARNO LIESENBERG, a citizen of the United States, residing in the city, county, and State of New York, have invented certain new and useful Improvements in Cigar-Holders, of which the following is a specification.

This invention has reference to an improved cigar-holding attachment to cups and trays, 10 said attachment being adapted to be sprung onto a dish or tray of suitable size, so that at a comparatively small expense a neat cigar-holder and ash-tray is obtained; and the invention consists of a cigar-holding attachment 15 composed of a circular frame provided with means for engaging with the rim of a dish and with upwardly-extending fingers, as will be fully described hereinafter, and finally pointed out in the claims.

20 In the accompanying drawings, Figure 1 represents a perspective view of my improved cigar-holding attachment, showing the same attached to a glass tray. Fig. 2 is a plan view of the same, and Fig. 3 is a modification.

25 Similar letters of reference indicate corresponding parts.

In Figs. 1 and 2 *a a* represent two diametrical wire arms which cross each other at right angles and are bent in downward direction at 30 their outer ends, as at *a'*, so as to form hooks to engage the rim of a glass, china, or other dish or tray *B*, such as are extensively used in ordinary tableware. To the intersecting arms *a a* is soldered a circular frame *C*, which 35 is likewise made of suitable wire and serves to support a scalloped wire frame *d*, the scallops of which extend in upright direction above the frame *d* to form fingers, which serve to support one or more cigars when placed on 40 the same. The ashes are readily dropped into the tray *B* through the intervention of the radial arms *a a* or when placing the cigar in position on the holder. The wire attachment is 45 preferably finished by plating or galvanizing and forms a neat and simple attachment to

glass or other dishes or trays that are found commonly in households. The large central opening *C* of the frame permits the ashes to readily fall into the tray below.

The modified form of attachment shown in 50 Fig. 3 is of sheet metal, and the circular frame *C* has integral downturned lugs or hooks *C'* formed thereon for engaging with the rim of the dish *B*, while *V*-shaped or scallop-shaped fingers *d'* are soldered to the upper surface of 55 the frame *C*.

The cigar-holder and tray is intended for use on card-tables when playing cards, as it forms a convenient support for the cigar while playing, and can be used as an ash-tray generally, as it can be furnished at a very small expense and forms a very neat and attractive cigar-holder and ash-tray for smokers.

Having thus described my invention, I claim as new and desire to secure by Letters 65 Patent—

1. A cigar-holding attachment, consisting of a frame having a large central opening, hooks or lugs at the side of the frame adapted to engage the rim of a dish or tray, and scallop-like fingers extending upwardly from the frame and adapted to hold cigars when placed radially on the frame, substantially as set forth.

2. A cigar-holding attachment, consisting 75 of intercrossing arms having downwardly-bent ends forming hooks adapted to engage the rim of a dish or tray, a circular frame attached to said arms and having a large central opening, and a scalloped continuous 80 holder-frame fixed to the upper side of the circular frame and adapted to hold cigars when placed radially thereon.

In testimony that I claim the foregoing as my invention I have signed my name in presence of two subscribing witnesses.

ARNO LIESENBERG.
